UNITED STATES PATENT OFFICE.

CHARLES J. GREENSTREET, OF WEBSTER GROVES, MISSOURI.

FURNACE AND FUEL-FEEDING DEVICE THEREFOR.

1,110,926.

Specification of Letters Patent. Patented Sept. 15, 1914.

Application filed September 26, 1912. Serial No. 722,383.

To all whom it may concern:

Be it known that I, CHARLES J. GREENSTREET, a citizen of the United States, and a resident of the city of Webster Groves, county of St. Louis, and State of Missouri, have invented a new and useful Improvement in Furnaces and Fuel-Feeding Devices Therefor, of which the following is a specification.

10 This invention relates particularly to furnaces adapted to burn coal dust and small particles of coal which are too fine to be burned on a grate.

Heretofore efforts have been made to devise apparatus for utilizing coal dust or comminuted particles of coal as a fuel for furnaces; but such devices have been unsatisfactory except in extensive plants.

15 The principal object of the present invention is to provide an apparatus for burning such fuel in small or moderate quantity and which will produce a comparatively uniform heat whose intensity is subject to control.

20 25 The invention consists in a new and improved furnace and fuel feeding mechanism, and particularly in the combinations and arrangements of parts thereof hereinafter described and claimed.

30 In the accompanying drawings, which form part of this specification, and wherein like symbols refer to like parts wherever they occur, Figure 1 is a side elevation of an apparatus embodying my invention, with 35 the furnace shown in vertical section; Fig. 2 is a plan of said apparatus; Fig. 3 is a central longitudinal section of the fuel hopper and feeding device, showing an end of the furnace and the fuel delivery pipe 40 and blower in side elevation; and Fig. 4 is a vertical section on the line 4—4 in Fig. 3, showing the blower and air inlet in elevation.

45 Referring to Figs. 1 and 2 of the drawings, my apparatus comprises a furnace 1 provided with a fuel inlet opening 2 at one end, and stack 3 at the opposite end through which the products of combustion leave the furnace. Within the furnace is 50 a combustion chamber 4, which is long and narrow and is provided with a bridge wall 5 at about midway of its length and an arch wall 6 near the outlet into the stack. The top of the bridge wall is higher than 55 the top of the fuel inlet opening. Between

the bridge wall and fuel inlet opening is a door opening 7 in the side wall of the furnace, through which access may be had to the combustion chamber. A delivery pipe 8 connects the outlet of a fan blower 9 with the fuel inlet opening 2, and over the air inlet to the blower is arranged a fuel hopper 10 and a motor driven mechanical device for regulating the feeding of powdered fuel into the blower casing. 60

Referring to Figs. 3 and 4, the fuel hopper 10 is mounted upon the top of a casing 11 containing the mechanical feed regulating device. The bottom part of the hopper extends down into the casing, and is fitted 70 with sliding bottom doors or gates 12, which are adjustable horizontally to regulate the width of the opening from the hopper into the casing 11, whereby the width of the downward moving column of fuel is regulated. This adjustment is effected by means of threaded rods 13 and thumb nuts 14 held in brackets 15 on the outside of the hopper. Spaced below the adjustable doors is a fixed 75 bottom 16 for the hopper, at both ends of which are elongated openings 17 into the casing 11. Two endless chains 18, running on sprocket wheels 19 fixed on shafts 20 and 21 mounted in the casing 11, pass through the openings 17 and over the bottom 80 of the hopper. The chains runs close to the opposite side walls of the casing, and are connected by metal angles or flights 22 forming a horizontal conveyor or scraper moving across the bottom of the hopper 85 toward the front opening 17.

A vertical slide 23 is adjustably mounted upon the front side of the hopper with its lower edge projecting down into the casing 11 adjacent to the front opening 17. A 90 leather strip 24 along the lower edge of the slide partly covers the opening and serves to limit the vertical width of the gap in the front wall of the hopper at its bottom, thereby controlling the thickness of the 95 stream of coal dust delivered by the conveyor. The shaft 20 is driven by a train of reduction gearing 25, 26, from the shaft 27 upon which is mounted a tight driving pulley 28 and a loose pulley 29, adapted to 100 carry a belt 30 from a pulley on the motor driven shaft 31. The blower 9 is driven by a belt 32 from another pulley on the shaft 31. At the back end of the casing 11 is an opening 33 extending across it near its bot- 105 110

tom. This opening is partly closed by a vertically sliding door 34, which may be secured at any suitable height by the thumb nuts 35.

5 In the bottom of the front of the casing 11 is an opening 36 and a passage 37 leads from this opening into the inlet opening 38 in the blower casing. The outer end of the passage 37 is provided with an air inlet opening 39 closed by a damper 40. This damper may be opened to allow air to enter the passage and mix with the air coming through the opening 33 and casing, and thus regulate the suction in the casing. Within 15 the blower casing is a centrifugal fan adapted to force the air and suspended coal particles entering its inlet through the delivery pipe 8 into the furnace. The blower delivery pipe 8 widens out in a horizontal direction and contracts in a vertical direction on nearing its outlet at the fuel inlet opening in the furnace wall. A slide valve 41 controlled by an adjusting screw 42 is placed in the delivery pipe near its outlet 20 into the furnace.

In the operation of the device the fuel, which is in the form of powder or finely divided particles, is placed in the hopper and the blower and conveyer are set in motion. The bottom doors of the hopper are adjusted until the opening between them is such that a thin column of fuel can pass through onto the hopper bottom, where its downward movement is checked. The bottom portion of this fuel column is picked up by the flights of the conveyer and delivered in a uniform stream through the front end opening in the hopper and into the stream of air entering the air inlet passage 37. The fine particles of fuel falling through the openings between the flights of the scraper are picked up by the whirling air currents in the end of the casing 11 caused by the suction of the blower and are carried 35 through the blower and delivery pipe into the furnace. The sliding door 34 and damper 40 are adjusted to create a swirling suction into the passage 37, with no back draft to blow coal dust into the atmosphere. The slide 23 is adjusted until the quantity of coal dust passing beneath it is just sufficient to be completely consumed by the quantity of air passing into the blower. The slide 40 valve 41 is set to give sufficient velocity to the blast of air and coal particles to cause a 45 strong blast against the bridge wall 5.

To start combustion in the furnace it is necessary to kindle a fire of wood or other suitable material therein before turning on the blast of air and coal particles. A blast of air alone may be used in starting the wood fire, and the fuel feeding device thrown into gear after a hot fire is thus started.

Having once put the furnace in operation,

in order to control the temperature therein it is only necessary to vary the speed of the motor which drives the blower and fuel feeding mechanism, and by the use of a thermostat, the temperature within the furnace 70 can be maintained substantially constant for any length of time desired and at any desired temperature from 1000 to 2400 degrees Fahrenheit. By heating the air before passing through the blower temperatures up to 75 3000 Fahrenheit can be attained and maintained substantially uniform by the use of my apparatus. The temperature of the furnace may be regulated also by simultaneously adjusting the coal feed regulating 80 slide 23 and the damper 40 in the air inlet 39.

Having described one form of apparatus embodying my invention, I do not desire to be limited thereto, but I claim as my invention the following:

1. A feeding apparatus for comminuted fuel comprising a hopper having an opening in its front wall adjacent to its bottom, a pair of doors arranged above said bottom 90 and spaced therefrom, said doors being movable to vary the width of the opening between them, a series of flights arranged across said bottom below said doors, means for moving said flights toward the front 95 wall of said hopper to control the passage of fuel through the opening therein, and means for causing an air current to pass beneath said bottom and across the opening in said wall. 100

2. A feeding apparatus for comminuted fuel comprising a hopper having an opening in its front wall adjacent to its bottom, a pair of doors arranged above said bottom and spaced therefrom, said doors being movable to vary the width of the opening between them, a series of flights arranged across said bottom below said doors, means for moving said flights toward the front 105 wall of said hopper to control the passage of fuel through the opening therein, means for causing an air current to pass beneath said bottom and across the opening in said wall, a passage having one end opening into the air and the other end terminating in a delivery duct, and means for drawing air through said passage and commingling it with said air current. 110

3. In an apparatus for burning comminuted fuel, a furnace having an elongated combustion chamber, one end of said combustion chamber having an outlet for the products of combustion and the other end thereof having a fuel inlet duct, and means for forcing a constant stream of air and commingled particles of coal dust through said inlet duct, said means comprising a blower, an air inlet duct for said blower, and mechanical means for feeding fuel continuously into said blower inlet duct, said 120 125 130

fuel feeding means comprising a hopper having an adjustable bottom opening, and a fixed bottom below said adjustable bottom opening, said hopper having an end opening above said fixed bottom, said end opening being located above said blower inlet duct, and means movable across said fixed bottom for transferring said fuel through said end opening into said blower inlet duct in a thin sheet.

4. An apparatus for feeding and burning comminuted fuel comprising a combustion chamber having a fuel inlet opening and an outlet opening for the products of combustion, a fire wall in said combustion chamber between said inlet and outlet openings, a blower having a delivery pipe communicating with said inlet opening, and means for feeding fuel in a substantially uniform sheet into said blower, said means comprising a hopper for said fuel, a flat bottom therefor having an elongated opening extending entirely across one end thereof, a wide endless conveyer having flights arranged to move the fuel endwise of said bottom and through said opening, means for actuating said conveyer, and a passage for air current crossing said elongated opening and discharging into the inlet of said blower whereby said fuel is uniformly commingled with air and delivered to said furnace.

5. An apparatus for feeding and burning comminuted fuel comprising a combustion chamber having a fuel inlet opening, a blower having a delivery pipe communicating with said inlet opening, and means for feeding fuel in a substantially uniform sheet into said blower, said means comprising a hopper for said fuel having a fixed bottom and an adjustable gate spaced above it, said hopper having an elongated opening extending across one end thereof below said gate, and a passage for air currents crossing said elongated opening and discharging into the inlet of said blower, said passage having an adjustable air inlet opening.

6. An apparatus for feeding and burning comminuted fuel comprising a combustion chamber having a fuel inlet opening and an outlet opening for the products of combustion, a blower having an intake duct and a delivery pipe communicating with said inlet opening, and means for feeding fuel in a substantially uniform stream into said blower intake duct, said means comprising a hopper for said fuel having an elongated opening extending across its bottom at one end thereof, a casing beneath said hopper, an endless conveyer having flights arranged to move the fuel endwise of said bottom and through said opening into said casing, means for actuating said conveyer, a slide extending from above said elongated opening into said casing, an opening in said casing communicating with said blower in-

take duct, and means in said duct controlling the velocity of the air entering said casing.

7. An apparatus for feeding and burning comminuted fuel comprising a combustion chamber having a fuel inlet opening and an outlet opening for the products of combustion, a blower having a delivery pipe communicating with said inlet opening, and means for feeding fuel in a substantially uniform sheet into said blower, said means comprising a hopper for said fuel having an elongated opening extending across its bottom at one end thereof, an endless conveyer having flights arranged to move the fuel endwise of said bottom and through said opening, means for actuating said conveyer, a casing below said hopper bottom having an adjustable opening at the end remote from said hopper bottom opening, a slide extending into the upper side of said casing and terminating above said hopper bottom opening, an eddy chamber in said casing below said hopper bottom opening, and a discharge chute from said casing into said blower.

8. In an apparatus for burning comminuted fuel, a furnace having an elongated combustion chamber, one end of said combustion chamber having an outlet for the products of combustion and the other end thereof having a fuel inlet duct, and means for forcing a constant stream of air and commingled particles of coal dust through said inlet duct, said means comprising a blower and mechanical means for feeding fuel continuously into the air inlet of said blower, said fuel feeding means comprising a hopper having a bottom opening, stationary means below said bottom opening for checking the fall of fuel through said bottom opening, said hopper having an end wall provided with an end opening below said bottom opening, means for adjusting the width of said end opening, an inlet duct for said blower under said end opening, and movable means for transferring said fuel through said end opening into said blower inlet duct.

9. A feeding apparatus for comminuted fuel comprising a fuel receptacle having a bottom opening extending lengthwise thereof, a wide flat bottom below said opening, said receptacle having an end wall terminating above said bottom and having an elongated opening of equal width to said bottom opening parallel to said bottom, laterally movable closures for said bottom opening whereby the width of the fuel passage may be adjusted, and the greater part of the fuel supported above said bottom, a series of flights longer than the width of said fuel passage arranged across said bottom with their ends beneath said closures, means for moving said flights lengthwise of said bottom whereby the fuel thereon is carried be-

neath and through the opening in said end wall without becoming compacted, and an adjustable closure for said end opening.

10. A feeding apparatus for comminuted fuel comprising a fuel receptacle having a bottom opening extending lengthwise thereof, a wide flat bottom below said opening, said receptacle having an end wall terminating above said bottom, laterally movable closures for said bottom opening whereby the width of the fuel passage may be adjusted and the greater part of the fuel supported above said bottom, a series of flights

longer than the width of said fuel passage arranged across said bottom with their ends 15 beneath said closures, and means for moving said flights lengthwise of said bottom whereby the fuel thereon is carried beneath said end wall without becoming compacted.

Signed at St. Louis, Missouri, this 20th 20 day of September, 1912.

CHARLES J. GREENSTREET.
